UNITED STATES PATENT OFFICE

2,597,500

APPARATUS FOR DRAWING ELONGATED METAL OBJECTS

Wallace E. Kerr, Youngstown, Ohio

Application April 28, 1948, Serial No. 23,684

8 Claims. (Cl. 205—7)

1

This invention relates to the metal drawing art and more particularly to improved methods and apparatus for drawing finite lengths of metal objects through a die in such manner that substantially all scrap loss is eliminated and in such manner that preliminary preparation of the blanks to be drawn by pointing is obviated. While the invention to be disclosed herein has some applicability in the field of bar drawing its greater and more important usefulness is in tube drawing and greater emphasis will accordingly be placed herein on the last mentioned use of the method and apparatus.

It has heretofore been commonly proposed, in the metal drawing art, to provide pushing grips in association with the drawing die to extrude the leading ends of blanks of uniform cross-sectional shape and dimension throughout their length through the drawing die sufficiently to enable them to be gripped by the draw carriage, the outward movement of which completes the drawing operation. It is one of the objects of the present invention to provide a novel and improved combination, in an assembly of the nature indicated, of pushing and pulling grip bits and mounting means therefor whereby the indicated operation may be carried out with greater facility and in a more dependable manner. Further, the novel combination of the grip bits while providing an entirely practicable machine is yet nevertheless operative to draw the entire length of uniformly cross-section blanks in a dependable manner to provide a finished product usable along its entire length, thus eliminating any need for cropping.

Another primary object of the invention is the provision of improved methods and apparatus for drawing the entire longitudinal extent of uniformly cross-sectioned tube blanks in such manner that the finished product is of uniform quality throughout its length, and free of grip marks. The process and apparatus of this invention is equally applicable in operations where in the thickness of the side wall of the tube is reduced, or in mere sinking operations.

A more specific object of the invention is the provision in tube drawing apparatus of the character capable of drawing the entire length of a uniformly cross-section blank of an improved driving arrangement for the pulling grip bits whereby the initiation of the drawing operation is facilitated and whereby static friction which may appear between the tube and die is more readily overcome.

Yet another object of the invention is the pro-

2

vision in tube drawing apparatus of the push-pointing type of an improved mandrel which is operative during the extruding or push-pointing phase of a complete cycle to be positioned in moving but operative location within the die which has a further relatively movable portion positioned within the tube blank opposite the pushing grips to prevent collapsing of the blank by these grips.

A still further object of the invention is the provision in a tube drawing system of the kind operative to reduce the side wall thickness of a tube blank throughout its entire longitudinal extent, of an improved plug mandrel, an improved operating mechanism for such mandrel, and of improved methods for operating and controlling the plug mandrel.

Other specific objects of the invention are the provision of an improved method for gripping an extruded end of a tube blank for completion of a tube drawing operation and of practical apparatus for carrying out such method.

The above and other objects and advantages of the invention will become apparent upon consideration of the following detailed specification and the accompanying drawing wherein there is disclosed a certain preferred embodiment of the invention:

In the drawing:

30 Figures 1 and 2 are schematic views, in plan, of tube drawing apparatus constructed in accordance with the principles of my invention, the views showing the relative positions of the parts at two separate stages during the drawing cycle;

35 Figure 1a is a fragmentary longitudinal section of certain of the parts of the assembly of Figures 1 and 2 when the parts are relatively positioned as shown in Figure 1;

40 Figure 2a is a view similar to Figure 1a but showing the parts as they appear when the machine is in the condition shown in Figure 2;

45 Figures 3 and 4 are generally similar to Figures 1 and 2 but show the relative positions of the parts at the third and fourth stage, respectively, of a complete drawing cycle;

50 Figures 3a and 4a are enlarged fragmentary sections through certain of the parts of the machine as they are relatively positioned in Figures 3 and 4, respectively;

Figure 5 is a view similar to Figure 1 but showing the parts in the last stage of the cycle of operation;

Figure 5a is a fragmentary longitudinal section through certain of the parts of Fig. 5;

Figure 6 is a transverse section taken along the line 6—6 of Figure 5; and

Figure 7 is a transverse section through the drawing mandrel, the view being taken along the line 7—7 of Figure 2a.

The illustrated apparatus of the invention comprises a draw carriage 10 mounting a grip block 11 and slidably supported on suitable ways 12 for movement toward and away from a die stand 13. While any suitable means may be employed to move the carriage 10 I preferably utilize a pair of double-acting hydraulic cylinders 14, the piston rods 15 of which extend outwardly to engage the carriage 10 to move the same away from and toward the die stand 13. Hydraulic fluid under pressure is arranged to be delivered to the rear ends of the cylinders 14 through conduits 16 to move the carriage 10 outwardly of the die while conduits 17 are provided to admit hydraulic fluid under pressure to the forward end of the cylinders 14 to retract the carriage 10. Recessed in the die stand 13 is a drawing die 18.

Positioned rearwardly of the die stand 13 and intermediate the cylinders 14 is a push-pointing mechanism comprising a grip block 20 and a pair of rigidly interconnected cylinders 21 receivable over rams 22 which are fixed on a base 23 bearing fixed relation to the die stand 13 and the ways 12. It should also be understood that the cylinders 14 are also fixed on the base 23. The push-pointing mechanism 20—22 and all its appurtenances, many of which are not shown, may be of the kind fully disclosed and claimed in my co-pending application Ser. No. 490,060, filed June 8, 1943, and entitled "Method and Apparatus for Drawing Tubes." As shown herein the grip block 20 slidably mounts a pair of serrated and wedge-shaped grip bits 24 and, as more fully explained in said co-pending application, the push-pointing mechanism includes means, not shown herein, for first closing the grip bits 24 onto the stock before hydraulic fluid pressure is admitted to the rams 22 to move the grip block 20 forwardly toward the die stand 13 and with means operative at the completion of a working stroke to open the grip bits 24 and to return the grip block back to its initial starting position. Hydraulic fluid pressure is admitted to the rams 22 through the conduits 25.

Slidably mounted in a wedge-shaped window formed in the grip block 11 of the carriage 10 is a pair of smooth faced wedge-shaped grip bits 26 which are contoured on their faces in the manner shown in Figure 6 to present four line contacts with a round bar or tubular member positioned between them. The absence of serrations or knurling on the gripping faces of the bits 26, however, requires the application of very extensive forces tending to move the grip bits toward each other to clamp a tube with sufficient rigidity to draw the same through the die and to accomplish the application of such heavy forces. I position anti-friction rollers 27 intermediate the inclined outer surfaces of the grip bits 26 and the adjacent inclined side walls of the wedge-shaped opening in the grip block 11. The grip bits 26 are, in actual practice, mounted in the grip block 11 in the manner more fully disclosed and claimed in my co-pending application Ser. No. 740,133, filed April 8, 1947, and entitled "Metal Drawing Apparatus."

As shown more clearly in said co-pending application Ser. No. 740,133 the grip bits are guided for movement parallel with the respective inclined side walls of the opening in the block 11

and in the apparatus disclosed herein means comprising a lever 28 is employed to move the grip bits 26 longitudinally to close and open the same with respect to work clamped therebetween.

As shown more clearly in Figures 1a and 2a the enlarged ends of the bits 26 are pivotally connected to a slidable yoke 29 which in turn is arranged to be shifted back and forth by pivotal movement of the lever 28 about its pivotal anchorage 19.

The frame of carriage 10 is formed with a longitudinally extending bore 30 in which is slidably received a sleeve 31 having a slit end 32 adapted to be positioned between the grips 26 as shown in Figures 1a, 2a and 6. The longitudinally extending slots in the end 32 of the sleeve 31 divides this end into four equal circumferential segments and is shown more clearly in Figure 6; each of the segments is arranged to have at least line contact with the gripping faces of the grips 26. For a purpose to be later described the end 32 of the sleeve 31 is retractable from the position intermediate the grips 26 and to provide for such manipulation of the sleeve 31 I provide a lever 33 which is pivoted to the carriage 10 at 34. Slidably received in the sleeve 31 is an arbor 35 which is slidable into and out of position between the grip bits 26. For advancing and retracting the arbor 35 I provide a lever 36. It should be understood that the levers 28, 33 and 36 are included herein to facilitate understanding of the principles of the invention, it being understood that in actual practice more suitable power operated means, as hydraulic cylinders, for example, may be employed to actuate the grip bits 26, the sleeve 31 and the arbor 35. This is particularly true as regards the arbor 35 since, as will appear later, the arbor in its forward position in the grip bits 26 may be employed to assist in the retraction of 40 the drawing mandrel when shifting from pushing operation to full drawing operation.

I provide a drawing mandrel of novel and improved construction comprised of a rod 37 mounting an elongated plug 38 having the shape and dimension required to form the proper internal opening through the tube to be drawn. While the plug 38 may be integral with the rod 37 it is usually made removable from the rod by means of a screw threaded connection, not shown. Rigidly secured to the plug 38 is a tag 39 which may be of slightly smaller cross-sectional area than the opening through the tube to be drawn so that it may readily pass through the tube blank and the opening in the die 18 for engagement by the grip bits 26 or by the sleeve 32 at the start of a drawing operation. The outer end portion of the plug 38 is preferably formed of a separable sleeve 40 constructed of sintered tungsten carbide or other material having superior abrasion resistant characteristics. As will appear later the block portion represented by the section 40 will be subjected to the greatest wear and it is accordingly desirable that material of the indicated nature be employed for this section. The portion 40 may be of cylindrical form and may be secured in position by a tapered stud bolt, not shown, integral with the tag 39 and screwed into the principal portion 38 of the mandrel.

Secured on the rod 37 is a collar 41 and interposed between the collar 41 and the plug 38 is a sleeve 42 and a coil spring 43 which normally biases the sleeve 42 into engagement with the plug 38. Sleeve 42 is, of course, slidably fitted on the shank 38 free to slide in the tube blank for a purpose to be hereinafter described.

The rod 37 of the drawing mandrel is connected by means of a universal joint 44 with a forward end of a piston rod 45 which in turn extends through an anchor block 43 which extends upwardly from the base 23. A collar 47' is secured in fixed position on the rod 45 and the block 46 is provided with a gate 47 which when closed is operative to prevent the passing through the anchor 46 of the collar 47', in a direction toward the die 18. Rod 45 is connected to a piston in a cylinder 48 which is slideable bodily in suitable ways 49 mounted on the base 23 and fluid pressure is arranged to be admitted to the rear end of cylinder 48 through conduit 50 to advance the drawing mandrel, and to the forward end of cylinder 48 through conduit 51 to retract the mandrel. It should be kept in mind, at this point, that such actuation of the drawing mandrel is limited in extent by the length of stroke of the cylinder 48. Rigidly connected with the outer housing of the cylinder 48 is a rod 52 connected with the piston in double-acting cylinder 53 which is also bodily slideable in the ways 49. Fluid pressure is admitted to the rear end of cylinder 53 through conduit 54 to move the cylinder 48 toward the die 18 and conduit 55 is provided to conduct fluid to the forward end of cylinder 53 to retract the cylinder 48. Rigidly connected with the outer housing of the cylinder 53 is a rod 56 connected with the piston in a double-acting cylinder 57 which is mounted in fixed relation on the base 23. A conduit 58 admits fluid under pressure to the rear end of cylinder 57 while a conduit 59 admits fluid to the forward end of cylinder 57.

To simplify the disclosure herein the various interlocking and sequentially operative electrical and hydraulic control circuits normally utilized for the actuation and control of the various component parts of the system including the grip bits 26, the arbor 35 and the cylinders 14, 21, 48, 53 and 57 have been omitted and it is believed that the operation of the system from the following full description of a complete cycle of operation will be readily understood.

At the start of a cycle of operation the parts are relatively positioned as shown in Figures 5 and 5a wherein the full retraction of both cylinders 48 and 53 frees the drawing mandrel entirely from the pushing assembly even though the latter is also fully retracted and in this position the mandrel may be readily tilted upwardly about the joint 44 to enable a tube blank to be slid over the outer free end of the mandrel. The mandrel is now re-aligned with the axis of the die and fluid is admitted to cylinder 48 through conduit 50 and through conduit 54 to cylinder 53 to advance the tube blank (designated by reference numeral 60) into abutting relation with the die 18 and to advance the working part of the mandrel through the die, all as shown in Figure 1a of the drawing. Gate 47 is open. At this time the split sleeve 32 is positioned between the grip bits 26 and after the carriage 10 is returned sufficiently to receive a substantial length of the projection 39 of the mandrel in the sleeve 32 the lever 28 is operated to close the grip bits 26 onto the split sleeve 32 which in turn moves into tight clamping engagement with the projection 39. Fluid pressure is now admitted to the conduits 25 and 16 and immediately the pushing grip bits 24 close onto the blank 60 after which the grip block 20 begins to move toward the die, all as explained in the above mentioned co-pending application Ser. No. 490,060 and simultaneously therewith the carriage 10 will be moved outwardly to pull

the mandrel further through the die and initiate the drawing of the blank through the die. It should be observed that due to the reduction in the side wall thickness of the blank the linear speed of the blank as it leaves the die will be greater than the linear speed of the blank as it enters the die and to prevent sliding of the mandrel in the blank either at or immediately following the die so as to reduce frictional losses as much as possible, I propose to proportion the flow of hydraulic fluid to the cylinders 14 and 21 in such manner as to compensate for this speed variation. Such regulation may be readily accomplished through the use of variable displacement hydraulic fluid pumps or through the use of flow control valves, as is well understood in the hydraulics art. Since the drawing mandrel moves along with the drawn portion of the tube as distinguished from an undrawn portion of the tube, it will be obvious that the mandrel must move faster than the push grips 24 which engage the exterior of the undrawn portion of the tube. The slideable sleeve 42 enables this to be accomplished while eliminating internal friction between the mandrel and tube and while yet guarding against the collapse of the tube by bits 24. It will be observed that the sleeve 42 is positioned between the bits 24 while the working portion 39 of the mandrel is substantially wholly outside the sphere of influence of the bits 24 at the start of the actual drawing operation. Continued actuation of the cylinders 14 and 21 will progress the mandrel and tube to the positions shown in Figures 2 and 2a. At this time the flow of fluid to the conduits 16 and 25 is discontinued but if the tube has not been extruded sufficiently to be clamped by the bits 26 the grip block 20 will be backed off and both cylinders 14 and 21 will be again actuated in a forward direction to effect further extrusion and drawing of the tube. Upon sufficient tube being extruded the flow of fluid to conduit 16 is discontinued to interrupt outward movement of the carriage 10. The grips 26 will now be opened by manipulation of the lever 28 and the sleeve 32 is retracted by manipulation of the lever 33. During the initial combined extrusion and drawing operation the forward movement of the drawing mandrel was allowed by movement of the piston in the cylinder 51, the cylinders 53 and 48 sliding bodily along the ways 49. After opening the bits 26 fluid is admitted to cylinder 57 through conduit 59 and to cylinder 53 through conduit 55 to retract the mandrel and anchor rod 45 to position the collar 47' immediately behind the gate 47 which is then closed. During such retraction the push-pointing mechanism which includes the grips 24 may be utilized to clamp and hold the blank 60 stationary. The dimensions of the parts are such that when the collar 47' is restrained against outward movement by the gate 47 the wear-resistant portion 40 of the drawing mandrel is positioned in operative relation in the die 18 as shown in Figures 3a and 4a.

Upon the mandrel portion 40 being positioned and locked in the die, the grips 26 will close onto the tube with the arbor 35 positioned inside the tube and fluid is now admitted to the conduits 16 leading to the cylinders 14 to effect outward travel of the carriage 10 and completion of the drawing operation. Upon the tube clearing the die the closing force on the grips 26 is removed and the grips 26 may be opened by the lever 28. At the same time the tube may be ejected from between the grips 26 and from the free end of the arbor 35 by operating lever 33 to slide the

sleeve 32 into the space between bits 26 formerly occupied by the outer end of the tube.

The desirability for the use of the sleeve 32 arises primarily from the desirability of making the block 11, grips 26 and associated roller races of reasonable length, for compactness, and since the wedge angle must be quite small to insure a heavy grip closing force. The range of movement of the bits 26 in a direction toward or away from each other is therefore necessarily quite limited and ordinarily it would not be possible for the same set of grip bits to adequately grasp both the tag 39 and the drawn tube which is formed on the working portion of the mandrel 38, 40. However, use of the sleeve 31, 32 may be dispensed with if the tube product has very light gauge side walls and if the diameter of the tag 39 is only slightly smaller than the diameter of the working portion of the drawing mandrel.

As clearly shown in Figures 3a and 4a, the outer end of the tag 39 is provided with a centrally disposed conical indentation which is complementary to the conical free end of the arbor 35. Thus when it is desired to retract tag 39 from the grip bits 26, i. e., when the mandrel is retracted to position the portion 40 in the die 18, the arbor 35 may be advanced longitudinally by operation of the lever 36, or other means employed, to assist in retracting the mandrel and the interlocking interconnection between the free end of the arbor 35 and the tag 39 will guide the arbor in the performance of this function. Further, this interconnection will guide the entrance of the arbor into the end of the tube as evident from a comparison of Figures 2a and 3a of the drawing which illustrate successive steps in the cycle of operation of the apparatus. It should be observed, however, that the force exerted on the mandrel through the arbor 35 is merely supplementary to the principal mandrel retraction force exerted by the double-acting cylinders 53 and 57. The guiding of the arbor 35 into the end of the tube inherently results in the axial alignment of the grip bits 26 with the tube 60 so that any possibility of the end of the grip bits 26 colliding with the end of the tube is avoided. This feature is useful since the available clearance for entering the grip bits 26 over the tube is small.

It can be readily shown that the force required to extrude a tube blank through an annular die opening is much greater than is the force required to pull the tube blank through the same die opening. Consequently, even through the initial extrusion of the tube blank in the present invention is materially aided by a heavy pull on the mandrel, the grips 24 must yet exert a very heavy force on the tube since in any case the beneficial force which can be applied to the mandrel in pulling direction can never exceed the axial frictional force between the mandrel and the tube blank. If smooth-faced pushing grips were employed they would have to be of very large size and their mounting block would have to be of such weight and dimension as to be impractical. Therefore, practical considerations do not permit the use of smooth-faced grip bits in the push-pointing mechanism and accordingly such grip bits are provided with serrations. These serrations, however, are sufficiently fine so as not to mark the stock to an extent which cannot be removed in the single pass through the drawing die. The invention, therefore, provides an entirely practical method and apparatus whereby elongated metal objects, both bars and tubes, may

be readily reduced and drawn throughout their entire axial length and finished free of any grip marks or other deformation requiring scrapping of any portions of their lengths.

5 The above specifically described embodiment of my invention should be considered as illustrative only as obviously many changes may be made therein without departing from the spirit or scope of the invention. Reference should therefore be had to the appended claims in determining the scope of the invention.

I claim:

1. Apparatus for drawing tubes comprising in combination a drawing die, a push-pointing device positioned ahead of said die and having means to grip the outer surface of a length of stock to extrude the same through said die, a draw carriage having gripping means positioned beyond said die, a mandrel having an elongated draw plug adjacent an end portion thereof and being reduced in diameter at said end portion, said gripping means on said carriage being operative to engage said reduced end portion of said mandrel and said extruded end portion of said stock length in succession, means to retract and mandrel, and means to anchor said mandrel in retracted position.

2. Tube drawing apparatus comprising in combination a drawing die, a push-pointing device die, a push-pointing device positioned ahead of said die and having means to grip the outer surface of a stock length to extrude an end portion of the same through said die, a draw carriage having gripping means positioned beyond said die, a drawing mandrel having an elongated sized portion adjacent an end portion thereof, said gripping means of said carriage being operative to engage said end portion to move said mandrel in said die simultaneously with the extrusion of said stock length by said push-pointing means, means to retract said mandrel, and means to anchor the same in retracted position, said gripping means on said carriage being also operative to engage the free-standing extruded end portion of said stock length.

3. A mandrel for tube drawing apparatus comprising in combination a shank, an elongated drawing plug secured to one end of said shank, a tag rigidly secured to and extending outwardly of the free end of said plug, a collar on said shank, a sleeve slidably mounted on said shank intermediate said collar and plug, and a coil spring mounted on said shank intermediate said collar and sleeve to normally maintain the latter in abutting relation with said plug.

4. A tube drawing apparatus having a drawing die, a push-pointer, a draw carriage, an elongated-plug type of mandrel having a tag projecting outwardly therefrom for gripping engagement by the draw carriage, means to retract said mandrel to a predetermined position relative to said die after movement of said mandrel through said die by engagement of said tag by said draw carriage, and releasable means to anchor said mandrel in said predetermined position.

5. Apparatus according to claim 4 further including a pair of cylinders mounted in tandem for retracting said mandrel to said predetermined position, one of said cylinders being fixed with respect to said die and the other of said cylinders being intermediate between the piston rod of said one of said cylinders and said

mandrel and being slidably mounted for movement toward and away from said die.

6. Apparatus according to claim 5 further including a third slidably mounted cylinder interconnected between the piston rod of said second mentioned cylinder and said mandrel, the arrangement being such that actuation of said second and third cylinders in a forward direction is normally operative to move said mandrel forwardly through said die into position for engagement by said draw carriage while actuation of said first and second mentioned cylinders in a reverse direction is operative to retract said mandrel to said predetermined position while said third cylinder is fully actuated in a forward direction.

7. Tube drawing apparatus comprising an elongated drawing plug, a tag rigidly secured to and extending outwardly of one end of said plug and adapted to be engaged by a draw carriage, an anchor rod secured to and extending axially outward of the other end of said drawing plug, means engaging the rearward extremity of said anchor rod to limit the forward movement of said anchor rod and to retract said anchor rod to a predetermined rearward position, and releasable means engaging said rod to retain the same in said predetermined rearward position.

8. Apparatus according to claim 7 further including a universal joint in said anchor rod whereby the forward portion of said anchor rod and said plug and tag may be tilted upwardly with respect to the axis of the rear portion of said anchor rod.
